UNITED STATES PATENT OFFICE.

MATHIAS J. HINDEN, OF DETROIT, MICHIGAN, ASSIGNOR TO HIMSELF, AND MARK FLANIGAN AND ANTHONY PARENT, OF SAME PLACE.

HYDROGEN-LAMP.

SPECIFICATION forming part of Letters Patent No. 275,045, dated April 3, 1883.

Application filed January 31, 1883. (No model.)

To all whom it may concern:

Be it known that I, MATHIAS J. HINDEN, of Detroit, in the county of Wayne and State of Michigan, have invented new and useful 5 Improvements in Hydrogen-Lamps; and I do hereby declare that the following is a full, clear, and exact description thereof, reference being had to the accompanying drawings, which form a part of this specification.

10 This invention relates to certain new and useful improvements in the construction of hydrogen-lamps; and the invention consists in the peculiar construction, arrangement, and combinations of the various parts, all as more 15 fully hereinafter set forth.

Figure 1 is a perspective view of the top of my improved lamp. Fig. 2 is a central vertical section of the same.

In the accompanying drawings, A represents 20 a suitable jar, preferably of glass, in which I place a mixture composed of about ten parts water and one part sulphuric acid, filling the jar to within about two inches of its top, and from this I produce gas, as hereinafter described. Over the mouth of the jar A, I place a cover, B, to the under face of which, and at the center thereof, I rigidly secure the pendent chamber C, the bottom of which is open and reaches to within a short distance of the bottom of the jar A. Within this chamber C, I hang a block of zinc, D. Rising from the top of the cover is the pipe E, in the shape of an inverted letter U, the discharge being directly over the hard-wood cup F, which is rigidly secured to the cover. This pipe E is provided 30 with a cock, G, the stem of which has secured to it the bell-crank lever H. One arm of the lever H is provided with a laterally-projecting pin, a, which rests upon the upper face of the spring I, one end of which is rigidly secured to the cover, while the opposite end, acting upon the pin above described, compels the lever to keep the cock closed, so that no gas can escape through the pipe, which has communication with the interior of the chamber C. The other arm of this bell-crank lever is faced upon its lower side with leather c, or other 40 suitable material, which, when the cock in the gas-pipe is closed, is closed over the mouth of the cup F. This cover not only keeps all particles of dust from entering the cup and accu-

mulating on the sponge, thus keeping it clean and always ready for use, but also extinguishes the flame, when the lever is released, by cutting off the supply of oxygen. In this 55 cup I place a small crucible, made of black-lead, and in this crucible I place a small quantity of platinum-sponge.

In practice, I first fill the jar with the mixture hereinbefore mentioned. I then insert 60 the chamber C with its block of zinc into the same, allowing the air in the chamber to escape through a proper vent in the gas-pipe until the mixture is at the same level in both the jar and the chamber. I then close the 65 vent, and the action of the mixture upon the zinc generates gas, which rises in the chamber and forces the water out at the bottom into the jar; and this "gas-making" continues until the solution has been expelled from the 70 chamber and the zinc is entirely out of the solution. By depressing the lever so as to allow gas to escape, such gas is expelled and discharged upon the platinum-sponge, such sponge becoming incandescent, and ignites the 75 gas, which will continue burning until it is all exhausted or the lever is released, allowing the spring to close the cock.

I am aware of Patents Nos. 78,755, 47,012, and 129,681, and make no claim to the construction shown thereby.

What I claim as my invention is—

1. In a hydrogen-lamp, the combination of the cup F, cock G, and bell-crank lever H, one end of which is adapted to cover the cup when 85 the cock is closed, substantially as described.

2. In a hydrogen-lamp, the combination of the cup F, cover B, cock G, bell-crank lever H, one end of which latter is adapted to cover the cup when the cock is closed, and pipe E, 90 substantially as described.

3. A hydrogen-lamp consisting of the jar A, cover B, chamber C, zinc D, pipe E, cup F, cock G, bell-crank lever H, one end of which latter is adapted to cover the cup when the 95 cock is closed, and spring I, all constructed, arranged, and operating substantially as described.

MATHIAS J. HINDEN.
